FUSE ASSEMBLY

Tomlinson Fort Johnson, Atlanta, Ga.

Application July 22, 1937, Serial No. 155,111

9 Claims. (Cl. 200--115)

This invention relates to fuses for high tension transmission lines and, among other objects, aims to provide a greatly simplified, relatively rugged and reliable detachable transformer fuse particularly designed for use in rural electrification installations. The main idea is to provide a fuse of this type suspended from a single support and having wedge action contact so that it will not loosen due to ordinary wind vibration and the like but can easily be removed and/or replaced by using the proper stick.

Other aims and advantages of the invention will appear in the specification, when considered in connection with the accompanying drawings, 15 wherein:

Fig. 1 is a side elevation of the preferred form of fuse assembly supported by a single insulator;

Fig. 2 is a front elevation of the fuse assembly shown in Fig. 1;

Fig. 3 is a sectional view taken on the line 3—3 of Fig. 1;

Fig. 4 is a side elevation, partly in section, of the fuse assembly, but showing it suspended from a transmission line;

Fig. 5 is a front view of the fuse assembly shown in Fig. 4;

Fig. 6 is a bottom plan view of Fig. 4; and

Fig. 7 is a top plan view of a stirrup support in the fuse assembly shown in Fig. 4.

Referring particularly to Figs. 1 to 3, the fuse assembly there shown is primarily intended for use on rural transmission lines which are usually supported on wood poles. Rural connections are usually made by mounting a transformer on a

35 pole or a wooden cross arm on the pole. In this instance, a transformer (not shown), is adapted to be mounted on a cross arm 10. The fuse assembly is also shown as being supported by the cross arm and is adapted to be connected to the 40 line by a tap conductor 11 which, in turn, may be tapped to the line by an ordinary line clamp (not shown).

Referring to Fig. 1, the fuse assembly is shown as being mounted on the cross arm by means of a single insulator 12 having the usual attaching bolt 13 extending through the arm. On the outer portion of the insulator there is mounted a stirrup 14 having a saddle 15 secured to the insulator by a U-bolt 16. The stirrup has a terminal connection for the tap conductor 11. The outer end of the stirrup is shown as being bifurcated and presents vertically extending channel shaped wings 17 having a flat contact surface 18. The outer ends of the two arms 19 of the stirrup are 55 connected by a cross bar 20 which also acts to

complete a wedge receiving socket for rigidly suspending the fuse unit.

In this example, the fuse unit is shown as comprising an ordinary fuse tube 21 on the upper end of which is suitably secured a collar 22 carrying an integral hook-shaped bracket 23 which has a wedge shaped contact member 24 preferably T-shaped in cross section and presenting an outer relatively wide vertical flange 25 adapted to engage and be seated firmly against the wedge 10 contact surface 18 of the stirrup. The inner inclined edge of the wedge is merely designed to engage the surface of the cross bar 20 to exert wedging action against the contact surface.

In this instance, the collar or ferrule 22 has 15 an integral eye 26 to receive the hook of a lineman's stick so that the fuse unit may be removed by raising the wedge 24 out of the stirrup. The fuse element 27 is shown as being electrically connected to the ferrule or collar and through 20 it to the wedge by means of a clamping member 28 held against a metal washer 29 on the upper end of the fuse tube. The clamp is securely gripped against the washer by means of an ordinary nut 30 on a stud 31. The fuse element 25 27 passes through the washer and has a head 32 on its upper end. It is adapted to be replaced when it is blown.

At the lower end of the fuse tube there is shown an elongated bracket 33 to one end of 30 which is connected a transformer tap conductor 34. The opposite end of the bracket extends some distance laterally from the end of the tube and carries a pivotally mounted flip-out link or arm 35 having a bifurcated free end through 35 which the fuse element extends. The lower end of the fuse element passes around the outer end of the bracket and is shown as being electrically connected thereto by means of another nut 36 on a bolt 37 extending upwardly through an opening in the bracket. The arrangement of the fuse element and flip-out arm is such that, when the fuse link blows out the arm 35 will immediately swing down and assist in withdrawing the burned off lower portion of the fuse element (see the 45 dotted positions of these parts in Fig. 4). In this instance, there is shown a small coil spring 38 having one end engaging the arm 35 to accelerate its flip-out movement. When the fuse element blows and the parts are in the position shown in dotted lines in Fig. 4, a lineman can quickly determine that the fuse has blown. Incidentally, there is sufficient slack provided in the transformer tap conductor 34 to permit the fuse unit to be lifted out as previously explained. 50 55

It is only necessary that the lineman engage the eye 26 of the fuse unit with his fuse removing stick and either replace the fuse element therein or substitute a new fuse unit. This operation may be performed by any unskilled mechanic.

In the form of stirrup described above, it is sometimes desirable to provide a spark gap or path to ground for lightning. To this end, the saddle 15 is shown as having an integral vertical arm or conductor 39. A second vertical arm 40 is clamped against the wooden cross arm 10 by a shoulder 41 on the insulator bolt 13. The arm 40 carries an adjustable horizontal rod 42 at its upper end, the free end of the rod being spaced from the arm 39 to provide a suitable gap. The inner end of the rod is screw threaded and extends through the arm 40. Nuts 43 on opposite sides of the arm 40 hold the rod in adjusted position.

Referring to the fuse assembly shown in Figs. 4 to 7 inclusive, the fuse unit is adapted to be suspended from the transmission line instead of a cross arm. The fuse unit and its wedge shaped contact member are identical with the form shown in Figs. 1 to 3. However, the stirrup 14 in this instance has an integral vertical arm 42 which carries a contact lamp 45 adapted to be tightened on the transmission wire 46 by means of an ordinary clamping bolt 47. This form of fuse assembly is well adapted to be suspended at any point from a transmission line between its posts or supports and the transformer tap conductor 24 may lead to a large transformer mounted on a platform or a base on the ground. Even though the wind may swing the transmission wire and vibrate the fuse unit, the wedge contact will prevent the fuse unit from being loosened. In fact, the more the fuse unit vibrates, the tighter will be the wedging engagement and the better the contact. The fuse unit may be inserted in and removed from the stirrup in the same manner as explained in connection with Figs. 1 to 3. The line clamp may be of any approved type and may be such as to be easily removable with an ordinary switch stick or other suitable lineman's implement.

From the foregoing description, it will be seen that the improved fuse assembly is very simple and rugged in its design. It is dependable in operation. It has no complicated parts or spring jaws and extra supports. It is easily manipulated by an unskilled mechanic, and it can be installed at a very low cost. In fact, it is eminently adapted for use in all rural electrification projects.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. In a fuse assembly of the class described, a horizontal metal stirrup having a vertical contact face and a horizontal cross bar spaced therefrom providing a fuse support; and a vertical fuse unit suspended from said stirrup having a self-tightening, wedge shaped contact member inserted through the upper side of the stirrup and removably engaged between the contact face and the cross bar.

2. In a fuse assembly of the class described, a support; an insulator on the support; a horizontal stirrup clamped on the insulator and hav-

ing spaced wedge receiving portions; means on the stirrup for connecting it to a transmission line; a vertical fuse unit; and hook shaped wedge means on the upper end of the fuse unit engageable with the spaced wedge receiving portions on the stirrup for removably suspending it from the stirrup.

3. In a fuse assembly of the class described, a fixed supporting member; a vertical insulated fuse tube; contact means on the upper end of the tube removably but normally rigidly connecting it to and suspending it solely from the supporting member; a fuse element within the tube having its upper end electrically connected to the contact means; a metal bracket secured to the lower end of the tube; and means on the bracket for securing the other end of the element and maintaining the element taut, said means including a spring urged member arranged to expel the lower portion of the element when it blows.

4. In a fuse assembly of the class described, a support; an insulator on the support; a horizontal stirrup having a cross bar clamped on the insulator; means on the stirrup for connecting it to a transmission line; a vertical arm on the stirrup; an adjustable member carried by the insulator support and spaced from the arm to provide a spark gap; a vertical fuse unit; and self-tightening means including a wedge shaped hook portion on the fuse unit engageable with the cross bar of the stirrup for removably suspending it from the stirrup.

5. In a fuse assembly of the class described, a stationary support; an insulator secured to the support; a horizontal stirrup clamped on the insulator; means on the stirrup for connecting it to a transmission line; a vertical fuse unit; and a hook shaped bracket on the upper end of the fuse unit having a self-tightening wedge portion removably engaged in the stirrup.

6. In a fuse assembly of the class described, a stationary support; an insulator secured to the support; a horizontal stirrup clamped on the insulator; means on the stirrup for connecting it to a transmission line; a vertical fuse unit; self-tightening wedge means on the fuse unit engageable with the stirrup for removably suspending it from the stirrup; and means at the lower end of the fuse unit automatically to remove a portion of the fuse element when it blows.

7. In a fuse assembly of the class described, a fuse unit having a hook-shaped contact member at one end; a supporting stirrup for suspending the fuse unit having outwardly diverging horizontal arms and a cross bar between the arms; a vertical flange member on the stirrup to provide a guiding and contact face coating with said hook-shaped contact member; and means on the stirrup for connecting it to a transmission line.

8. In a fuse assembly of the class described, a fuse unit having contact means at its upper end by which it may be suspended; a supporting stirrup having outwardly diverging horizontal arms and a cross bar between the arms; a vertical flange member on the stirrup to provide a guiding and contact face coating with said contact means to support the fuse unit; an integral arm extending upwardly from said stirrup; and means at the upper end of the arm to secure it to a transmission line.

9. In a fuse assembly of the class described, a fuse unit; a supporting stirrup for suspending the fuse unit having outwardly diverging hori-

5 zontal arms and a cross bar between the arms; a vertical flange member on the stirrup to provide a guiding and contact face; a hook like wedge shaped contact member at the upper end of the fuse unit inserted through the upper side of the stirrup between the cross bar and the

flange member; an integral arm extending upwardly from the stirrup; and clamp means on the upper end of the arm to connect the arm to a transmission line so that the stirrup and fuse unit are supported solely by the line.

TOMLINSON FORT JOHNSON.
